UNITED STATES PATENT OFFICE.

ROBERT CLYDE CAMERON, OF GOLDFIELD, NEVADA.

DEVICE FOR REMOVING STUCK DRILLS.

1,171,317.

Specification of Letters Patent. Patented Feb. 8, 1916.

Application filed October 17, 1914. Serial No. 867,121.

To all whom it may concern:

Be it known that I, ROBERT CLYDE CAMERON, a citizen of the United States, and a resident of Goldfield, in the county of Esmeralda and State of Nevada, have invented a new and Improved Device for Removing Stuck Drills, of which the following is a full, clear, and exact description.

My invention has for its object to provide a device of the character described having a sleeve with an outer thread with means for securing a drill in the sleeve so that the sleeve may be turned relatively to a second sleeve having an inner thread with which the first thread meshes. By this means it is possible to move the first sleeve together with the drill, longitudinally of the second mentioned sleeve, thereby withdrawing the drill.

Additional objects of the invention will appear in the following specification in which the preferred form of my invention is disclosed.

In the drawings similar reference characters refer to similar parts in all the views in which—

Figure 1 is a sectional view showing how my invention is used; Fig. 2 is an enlarged end view of Fig. 1 showing the drill in section; and Figs. 3 and 4 are views showing a modified form of the invention.

By referring to the drawings it will be seen that a member 5 is provided which has a foot 6 at one end for disposal against the rock 7 at an opening 9 in which a drill 8 is disposed. This member 5 has a threaded opening 10 in which meshes a thread 11 on a sleeve 12 and it will be seen that when the sleeve 12 is secured to the drill 8 and is rotated relatively to the member 5, the sleeve together with the drill, will be moved longitudinally of the member 5 and in this manner be withdrawn from the opening 9 in the rock 7.

The end of the sleeve 12 has a flange 13 which has an opening 14 which forms a continuation of the opening in the sleeve 12. Mounted on the flange 13 there is a disk 15 which has an annular shoulder 16 engaging the periphery of the flange 13 which is also annular. The disk 15 is held mounted on the flange 13 by the lugs 17 which engage the inner face of the flange 13 and which are secured to the disk 15 by the pins or bolts 18. The disk 15 like the flange 13, has an opening 19 through which the

drill 8 is disposed, the disk 15 also having a recess 20 which is disposed at one side of the opening 19 and which is connected therewith. The outer wall of this recess 20 is eccentric in shape from the point 21 to the point 22 and relatively to the opening 19 beyond the point 22, the outer wall of the recess 20 may be curved as at 23 substantially concentric with the drill. In that portion of the recess 20 having the eccentric wall there is disposed a cam finger or wedge 24 which is pivoted by the pin 25, this pin 25 being secured to the flange 13. It will, therefore, be seen that when the disk 15 is rotated to the left that the cam finger or wedge 24 will be gripped between the drill 8 and the disk 15 to lock the drill 8 and the flange 13 to the disk 15 so that with the further rotation of the disk 15, by means of bars inserted in the openings 26, the drill 8 will be held to the sleeve 12 while the sleeve 12 is rotated relatively to the member 5, thereby moving the sleeve 12 and the drill 8 longitudinally of the member 5. The member 5 is prevented from rotating with the sleeve 12 by means of the pressure at its foot 6 against the rock 7.

When the disk 15 is rotated to the right it will move to a position where the cam finger or wedge 24 will be disengaged from the gripping contact between the drill 8 and the disk 15 to permit the operator to free the sleeve 12 and the disk 15 from the drill to make it possible for the operator to obtain another grip on the drill nearer its point and when the drill has been completely removed from the opening 9 in the rock 7 to free the device so that it may be used at another time or place.

In order to take the strain off of the cam finger or wedge 24, the rear of the cam finger or wedge 24 is curved at 26 concentrically with the pin 25 and a support 27 is provided which is secured to the flange 13 and which is disposed in the opening 20, this support 27 having a face 28 which is curved concentric with the pin 25 and which is engaged by the curved end 26 of the cam finger or wedge 24.

In Figs. 3 and 4 a modified form of the invention is disclosed. In this form of the invention the sleeve 12^a has a thread similar to that shown in Fig. 1 which meshes in a threaded opening 10^a in a member 5^a, the sleeve 12^a having a flange 13^a with openings 26^a in which a bar may be inserted to permit

the convenient turning of the flange 13^a which is secured to the sleeve 12^a and which will, therefore, serve to rotate the sleeve 12^a. As will be seen by referring to the drawings 5 the flange 13^a has an opening 14^a which is a continuation of the opening in the sleeve. The flange 13^a also has a recess 29 which is curved away from each side of the opening 14^a at 30 and which has a groove 31 with 10 sides 32 which are at angles with its rear 33. As shown in Fig. 3 of the drawings, the groove 31 tapers inwardly, a wedge 34 being provided which fits the recess and the groove 31 so that when it is driven home it will 15 secure the drill 8 to the flange 13^a and to the sleeve 12^a, thereby making certain of the rotation of the drill 8 with the rotation of the flange 13^a.

Having thus described my invention I 20 claim as new and desire to secure by Letters Patent:

1. In a device of the class described, a sleeve having an outer thread, a member having a threaded opening in which the 25 thread on the sleeve meshes, a flange at an end of the sleeve with an opening registering with the opening in the sleeve, a disk rotatably mounted on the flange and provided with an opening registering with the opening 30 in the flange, and having a recess at one side of the opening, the outer wall of which is eccentric relatively to the axis of the opening, and a cam finger pivoted to the flange and disposed in the recess in the disk to be 35 embraced between the disk at the outer wall of the recess and a drill which may be disposed through the opening.

2. In a device of the class described, a sleeve having an outer thread, a member 40 having a threaded opening in which the thread on the sleeve meshes, a disk for rotating on the sleeve and provided with an opening registering with the opening in the sleeve, and a recess at one side of the opening, the outer wall of which diverges relatively to the plane of the opening in the sleeve, and a cam disposed in the recess for the purpose specified.

3. In a device of the class described, a 50 sleeve having an outer thread, a member having a threaded opening in which the thread on the sleeve meshes, a disk for rotating on the sleeve and provided with an opening registering with the opening in the sleeve, and a recess at one side of the opening, the outer wall of which diverges relatively to the plane of the opening in the sleeve, and a pivoted cam disposed in the recess for the purpose specified.

4. In a device of the class described, a 55

sleeve having an outer thread, a member having a threaded opening in which the thread on the sleeve meshes, a flange at an end of the sleeve registering with an opening in the sleeve, a disk rotatably mounted on 65 the flange and provided with an opening registering with the opening in the flange, and having a recess at one side of the opening, the outer wall of which is eccentric relatively to the axis of the opening in the flange, 70 and a cam finger pivoted to the flange and disposed in the recess, the rear of the cam finger being curved concentric with its pivot and a support for the cam finger secured to the first disk and having a curved face with 75 which the rear of the curved finger engages.

5. In a device of the class described, a member having a threaded opening, a sleeve having an outer thread meshing in the threaded opening, a disk secured to the sleeve 80 and provided with an opening registering with the opening in the sleeve and having a tapering recess, and a wedge disposed in the recess normally embraced by the disk, and a drill disposed in the opening. 85

6. In a device of the class described, a member having a threaded opening, a sleeve having an outer thread meshing in the threaded opening, a disk mounted on the sleeve and provided with an opening registering with the opening in the sleeve and having a recess connected with the opening and tapering longitudinally of the sleeve, the recess in cross section curving outwardly 90 from the opening and having a groove the 95 sides of which are disposed at an angle to its end and a wedge disposed in and fitting the recess for the purpose specified.

7. In a device of the class described, a sleeve having an outer thread, a member having a threaded opening in which the 100 thread on the sleeve meshes, a disk disposed substantially coaxially with the sleeve and rotatable relatively thereto, the disk having an opening registering with the opening in the sleeve, and a recess at one side of the opening, the outer wall of the recess being eccentric relatively to the axis of the sleeve, a cam finger pivoted relatively to the sleeve, and disposed in the recess in the disk to be 105 embraced between the disk at the outer wall of the recess and a drill which may be disposed through the opening in the sleeve.

In testimony whereof I have signed my name to this specification in the presence of 115 the two subscribing witnesses.

ROBERT CLYDE CAMERON.
